H. L. ISHAM, OF PLATTSBURG, NEW YORK.

Letters Patent No. 69,441, dated October 1, 1867.

IMPROVED BED-BOTTOM.

The Schedule referred to in these Letters Patent and making part of the same.

TO ALL WHOM IT MAY CONCERN:

Be it known that I, H. L. ISHAM, of Plattsburg, in the county of Clinton, and in the State of New York, have invented certain new and useful Improvements in Bed-Bottoms; and do hereby declare that the following is a full, clear, and exact description thereof, reference being had to the annexed drawings, and to the letters of reference marked thereon, making a part of this specification.

In the accompanying drawings, A represents the bedstead, within which is set the bed-bottom. This bed-bottom is composed of series of horizontal slats C C C, which are connected to cross-pieces B B at each end. Upon the under sides of the cross-pieces B B is a series of metallic loops, e, which encircle rubber bands a a. Each end of the slats C is provided with two narrow slots x x, (see fig. 4,) which open in the end of the said slats, and into which are passed the bands a a. All of the slats being thus attached to a corresponding number of bands, a leather belt, D, is wound over and under every slat at each end of the bed, thus securing them in place, and preventing them from becoming too close to each other or too far off. A bed-bottom thus formed will be found elastic and durable, and can be readily adjusted.

Having thus fully described my invention, what I claim, and desire to secure by Letters Patent, is—

The combination of the slats C C with narrow slots at each end for securing the bands a a that connect the slats to the cross-pieces B, and additionally connecting the slats, one with the other, by the belts D D, whereby the slats are prevented from turning, as herein specified.

In testimony that I claim the foregoing I have hereunto set my hand this 2d day of July, 1867.
